UNITED STATES PATENT OFFICE

2,659,037

DEVICE FOR THE IGNITION AND THE OPERATION OF A GAS FILLED ELECTRIC DISCHARGE APPARATUS

André Claude, Paris, France

Application June 18, 1948, Serial No. 33,883
In France July 28, 1941Section 1, Public Law 690, August 8, 1946
Patent expires July 28, 1961

13 Claims. (Cl. 315—233)

1

The present application is a continuation-in part of my application Serial No. 657,964, filed March 29, 1946, now abandoned.

My invention relates to devices for starting and operating alternating current actuated electric discharge apparatus containing a gaseous atmosphere, which discharge apparatus require the application of a higher voltage for starting them than is required for the subsequent normal operation thereof.

For this purpose, it is known to use resonance circuits comprising a reactance coil in series with the source of current and a condenser connected to the terminals of the assembly comprised of the discharge apparatus and a second reactance coil in series with the latter. When the resonance circuit is energized and the discharge apparatus then does not start, a very high no-load current will flow in the condenser branch. This high no-load current will damage the coil through which it flows unless an appropriate cut-out is provided.

The principal object of the present invention is to avoid this drawback.

Another object is to provide a resonance effect circuit in which it is not necessary that the condenser be of so high a capacity as in the above circuit.

A further object is to avoid the rush of current that takes place when an electric discharge apparatus is fed by a usual resonance effect device and that submits the electrodes to an excessive strain.

Still another object is to render the shape of the representative curve of the current in the discharge apparatus, that is the curve giving the intensity of the discharge current versus time, as near as desired to that obtained when the apparatus is fed from the source directly, that is only through a reactance coil.

Yet another object is to reduce the loss of power in the device while satisfying all the conditions necessary for a proper working of the apparatus.

It is also another object to obtain a high power factor without connecting a condenser across the main terminals.

In case the discharge apparatus is intended for illumination, still another object is to obtain a satisfactory stability in the luminous flux, and to so construct the device that, for a variation of 10% in the feeding voltage, the luminous flux will vary only by 1%, or even only by 10%.

According to the invention, a third reactance coil is used in series with the above mentioned condenser, the first and second coils being mag-

2

netically independent and the three reactance coils and the condenser being so dimensioned that the intensity of the current circulating at no load in the device—i. e. when no current flows through the discharge apparatus although the resonance device is branched to an alternative source of current—will be sufficiently low to ensure that the first coil, which is dimensioned for a normal heating during operation, will not overheat due to a prolonged flow of no-load current. The intensity of the no-load current may be maintained lower than 1.5 times the operating current, and even, for instance, substantially equal to the latter.

The first and third reactance coils and the condenser form a resonant circuit which must be in partial resonance at the frequency of the source of current. The voltage of this source must be sufficient to feed "directly," that is only through a reactance coil, the discharge apparatus after the discharge in the latter has started.

The shape of the curve of the discharge current versus time may be maintained as near as required to the theoretical sinusoid, this improvement of the form depending much more on the importance of the reactance of the third coil than on an adjustment of the capacity. Satisfactory results with regard to the shape of the current curve, as in other respects, are obtained by so dimensioning the three coils and the condenser that during normal operation the voltage at the terminals of the condenser be at least 1.5 or about 1.5 times the voltage at the terminals of the apparatus.

A substantial reduction in the size of the reactance coils is obtained by magnetically coupling the first and third reactance coils, the discharge apparatus being provided with a device, known per se, for lowering its starting voltage. Experience has proved that such a change in the above feed device makes it possible to obtain, as when no coupling is used, a good shape of the current curve, the omission of the device for lowering the starting voltage when this coupling is used or the coupling of the second reactance coil with one of the others result in an unsatisfactory shape of this curve, unless the coupling is very low.

My invention will be better understood from the following description taken in connection with the accompanying drawing and its scope will be pointed out in the appended claims.

In the drawings:

Fig. 1 is a schematic view of a circuit embodying one form of the present invention;

Fig. 2 is another schematic view of another cir-

cuit embodying a modified form of the present invention.

In the drawings, in which similar reference characters designate similar parts, there is shown in Fig. 1 a circuit including main terminals 13 and 14. The voltage of the current supplied by the main is 220 and the frequency 50 cycles per second. 5 is the discharge apparatus, of the positive column type, comprising a tubular envelope containing a gaseous atmosphere, such as a few millimeters of argon and a drop of mercury, and two monopolar electrodes 11, 12, of the thermionic and self heating type spaced 930 millimeters apart. The starting voltage of the electric discharge apparatus is about 360 volts and the operation voltage is about 125 volts. The resonance effect device comprises a 2 microfarad condenser 4 and three inductance coils 1, 2, 3, wound on independent magnetic circuits. The self-inductance value of coil 1 is 1.6 henries, that of coil 2 is 1 henry and that of coil 3 is 2.1 henries. The no-load voltage of this resonance effect device, when fed by the above source of current, is about 370 volts.

Once the starting or ignition of the discharge apparatus has been effected, it may be advantageous to modify the connections of the fundamental arrangements. For instance, after ignition, it is possible to connect the two reactance coils 1 and 3 in parallel, in known manner—by means of the connection shown in dotted lines in Fig. 1 and comprising a switch 6 controlled if desired by a relay—so that the condenser is then directly connected across the terminals 13, 14 of the main or line from the source of current. According to the invention it is possible to so dimension or construct the different elements that the intensity of current flowing in the discharge apparatus at the end of the starting period is substantially equal to that of the operating current obtained after connecting reactance coils 1 and 3 in parallel. In case of the switch being controlled by an automatic relay, the switching-on can be delayed, without appreciable inconvenience, the above mentioned current intensity remaining substantially constant. Moreover it should be noted that the dimensioning of the elements thus effected frequently suffices for ensuring a satisfactory feeding of the apparatus, even if said connecting in parallel is not effected. The addition of the relay is simply an improvement securing a better power factor and a slight diminution of the losses in the apparatus. If, for any reason, the relay does not operate, the apparatus continues nevertheless to operate under conditions very good in all respects.

Referring to Figure 2, reference numerals 13a and 14a designate as in Fig. 1 the terminals of the mains, the voltage across which is 220 volts. The current has a frequency of 50 cycles per second. Reference numeral 5a is the discharge apparatus, of the positive column type, comprising a tubular envelope containing a gaseous atmosphere such as a few millimeters of argon and a drop of mercury, two main monopolar electrodes: 11a, 12a of the thermionic and self-heating type spaced 930 millimeters apart, and two auxiliary electrodes 7a, 8a, each 2 millimeters distant from the nearest main electrode. The value of the resistances 9a, 10a, connecting each of the auxiliary electrodes to the farthest main electrode is 20,000 ohms. The striking voltage of the electric discharge apparatus is about 320 volts and the operation voltage is about 125 volts.

The resonance effect device comprises a 2

microfarad condenser 4a and three inductance coils 1a, 2a, 3a. The coils 1a and 3a are wound in the same direction on the same magnetic circuit, the self-inductance value of coil 1a being 1.4 henries and that of coil 3a being 1.95 henries. The coil 2a, the self-inductance value of which is 1 henry, is wound on another magnetic circuit. The no-load voltage of the resonance effect device, when fed by the above source of current, is about 370 volts.

As described in connection with Figure 1, the contingent utilisation of a switch 6 to be closed after ignition is contemplated; the known circuit is then obtained which comprises a condenser 4a which is utilised for improving the power factor, and a ballast-choke connected in series with the discharge apparatus; the choke consists here of the inductance coils 1a and 3a in parallel and of the coil 2a.

What I claim is:

1. In combination, an alternating current supply line of a given frequency having two conductors, a gaseous electric discharge apparatus the starting voltage of which is substantially higher than the voltage sufficient for ensuring a stable operation and the operating voltage of which is sufficiently low for the direct feeding by the supply line after starting, said discharge apparatus having two terminals, a first reactance coil, a connection between one end of said first reactance coil and one conductor of said current supply line, a second reactance coil, a connection between one end of said second reactance coil and the other end of said first reactance coil, a connection between the other end of said second reactance coil and one terminal of the discharge apparatus, said second reactance coil being magnetically independent of said first reactance coil, a connection between the other terminal of the discharge apparatus and the other conductor of the current supply line, a third reactance coil, said third reactance coil being magnetically independent of said second reactance coil, a connection between one end of said third reactance coil and said one end of the second reactance coil, a condenser having two terminals, a connection between one terminal of said condenser and the other end of said third reactance coil, a connection between the other terminal of the condenser and said other terminal of the discharge apparatus, said first and third reactance coils and said condenser forming a circuit in partial resonance at the frequency of the current supply line.

2. The combination of claim 1, including a switch having two terminals, one of said terminals being connected to said other terminal of the third reactance coil and the other terminal of the switch being connected to said one end of the first reactance coil.

3. The combination of claim 1, including a switch having two terminals, one of said terminals being connected to said other terminal of the third reactance coil and the other terminal of the switch being connected to said one end of the first reactance coil, and in which the dimensioning of the three reactances and of the condenser is such as to render the no-load current of the current supply line sufficiently low to avoid damage to said first reactance coil when said first reactance coil is so dimensioned as to avoid exceeding the conventionally allowed heating during the normal operation of the discharge apparatus.

4. The combination of claim 1, including a

switch having two terminals, one of said terminals being connected to said other terminal of the third reactance coil and the other terminal of the switch being connected to said one end of the first reactance coil, and in which the dimensioning of the three reactances and of the condenser is such as to render the no-load current of the current supply line lower than 1.5 times the operating current of said current supply line.

5. In combination, an alternating current supply line of a given frequency having two conductors, a gaseous electric discharge apparatus the starting voltage of which is substantially higher than the voltage sufficient for ensuring a stable operation and the operating voltage of which is sufficiently low for the direct feeding by the supply line after starting, said discharge apparatus having two terminals, a first reactance coil, a connection between one end of said first reactance coil and one conductor of the current supply line, a first assembly comprising said discharge apparatus, a second reactance coil and a connection between one terminal of said discharge apparatus and one end of said second reactance coil, said first assembly being connected across the other end of said first reactance coil and the other conductor of the current supply line, a second assembly comprising a condenser having two terminals, a third reactance coil and a connection between one terminal of said condenser and one end of said third reactance coil, said second assembly being connected across said other end of said first reactance coil and said other conductor of the current supply line, said second reactance coil being magnetically independent of said first and third reactance coils and said first and third reactance coils and said condenser forming a circuit in partial resonance at the frequency of the current supply line.

6. In combination, an alternating current supply line of a given frequency having two conductors, a gaseous electric discharge apparatus the starting voltage of which is substantially higher than the voltage sufficient for ensuring a stable operation and the operating voltage of which is sufficiently low for the direct feeding by the supply line after starting, said discharge apparatus having two terminals, a first reactance coil, a connection between one end of said first reactance coil and one conductor of the current supply line, a first assembly comprising said discharge apparatus, a second reactance coil and a connection between one terminal of said discharge apparatus and one end of said second reactance coil, said first assembly being connected across the other end of said first reactance coil and the other conductor of the current supply line, a second assembly comprising a condenser having two terminals, a third reactance coil and a connection between one terminal of said condenser and one end of said third reactance coil, said second assembly being connected across said other end of said first reactance coil and said other conductor of the current supply line, said second reactance coil being magnetically independent of said first and third reactance coils, said first and third reactance coils and said condenser forming a circuit in partial resonance at the frequency of the current supply line, and the dimensioning of the three reactances and of the condenser being such as to render the no-load current of the current supply line sufficiently low to avoid damage to said first

reactance coil when said first reactance coil is so dimensioned as to avoid exceeding the conventionally allowed heating during the normal operation of the discharge apparatus.

5. The combination of claim 6 in which the dimensioning of the three reactances and of the condenser is such as to render the no-load current of the current supply line lower than 1.5 times the operating current of said current supply line.

10. The combination of claim 5, in which the dimensioning of the three reactances and of the condenser is such as to render the no-load current of the current supply line sufficiently low to avoid damage to said first reactance coil when said first reactance coil is so dimensioned as to avoid exceeding the conventionally allowed heating during the normal operation of the discharge apparatus.

15. The combination of claim 5, in which the dimensioning of the three reactances and of the condenser is such as to render the no-load current of the current supply line lower than 1.5 times the operating current of said current supply line.

20. The combination of claim 5, in which the dimensioning of the three reactances and of the condenser is such as to render the operating voltage at the terminals of the condenser at least 30 equal to 1.5 times the operating voltage at the terminals of the electric discharge apparatus.

25. In combination, an alternating current supply line of a given frequency having two conductors, a gaseous electric discharge apparatus

30. the starting voltage of which is substantially higher than the voltage sufficient for ensuring a stable operation and the operating voltage of which is sufficiently low for the direct feeding by the supply line after starting, said discharge

35. apparatus having two terminals, a first reactance coil, a connection between one end of said first reactance coil and one conductor of the current supply line, a first assembly comprising said discharge apparatus, a second reactance coil and a connection between one terminal of said discharge apparatus and one end of said second reactance coil, said first assembly being connected across the other end of said first reactance coil and the other conductor of the current supply line, a second assembly comprising a condenser having two terminals, a third reactance coil and a connection between one terminal of

40. said condenser and one end of said third reactance coil, said second assembly being connected across said other end of said first reactance coil and said other conductor of the current supply line, said first reactance coil being magnetically independent of said first and third reactance coils and said first and third reactance coils and said condenser forming a circuit in partial resonance at the frequency of the current supply line, and the electric discharge apparatus

45. being provided with a device for lowering the starting voltage of the gaseous electric discharge apparatus.

50. 11. In combination, an alternating current supply line of a given frequency having two conductors, a gaseous electric discharge apparatus the starting voltage of which is substantially higher than the voltage sufficient for ensuring a stable operation and the operating voltage of which is sufficiently low for the direct feeding by the supply line after starting, said discharge

55. apparatus having two terminals, a first reactance coil, a connection between one end of said first reactance coil and one conductor of the current supply line, a second assembly comprising a condenser having two terminals, a third reactance coil and a connection between one terminal of

60. said condenser and one end of said third reactance coil, said second assembly being connected across said other end of said first reactance coil and said other conductor of the current supply line, said first reactance coil being magnetically independent of said first and third reactance coils and said first and third reactance coils and said condenser forming a circuit in partial resonance at the frequency of the current supply line, and the electric discharge apparatus

65. being provided with a device for lowering the starting voltage of the gaseous electric discharge apparatus.

12. In combination, an alternating current supply line of a given frequency having two conductors, a gaseous electric discharge apparatus the starting voltage of which is substantially higher than the voltage sufficient for ensuring a stable operation and the operating voltage of which is sufficiently low for the direct feeding by the supply line after starting, said discharge

apparatus having two terminals, a first reactance coil, a connection between one end of said first reactance coil and one conductor of said current supply line, a second reactance coil, a connection between one end of said second reactance coil and the other end of said first reactance coil, a connection between the other end of said second reactance coil and one terminal of the discharge apparatus, said second reactance coil being magnetically independent of said first reactance coil, a connection between the other terminal of the discharge apparatus and the other conductor of the current supply line, a third reactance coil, said third reactance coil being magnetically independent of said second reactance coil, and being magnetically coupled with said first reactance coil, a connection between one end of said third reactance coil and said one end of the second reactance coil, a condenser having two terminals, a connection between one terminal of said condenser and the other end of said third reactance coil, a connection between the other terminal of the condenser and said other terminal of the discharge apparatus, said first and third reactance coils and said condenser forming a circuit in partial resonance at the frequency of the current supply line, and the electric discharge apparatus being provided with a device for lowering the starting voltage of the gaseous electric discharge apparatus.

13. In combination, an alternating current supply line of a given frequency having two conductors, a gaseous electric discharge apparatus the starting voltage of which is substantially higher than the voltage sufficient for ensuring a stable operation and the operating voltage of which is sufficiently low for the direct feeding by the supply line after starting, said discharge apparatus having two terminals, a first reactance coil, a connection between one end of said first reactance coil and one conductor of said current

supply line, an assembly comprising a second reactance coil, said discharge apparatus and a connection between one terminal of said discharge apparatus and one end of said second reactance coil, said second reactance coil being magnetically independent of said first reactance coil, a connection between one end of said assembly and the other end of said first reactance coil, a connection between the other end of said assembly and the other conductor of the current supply line, a third reactance coil, said third reactance coil being magnetically independent of said second reactance coil, a connection between one end of said third reactance coil and said other end of the first reactance coil, a condenser having two terminals, a connection between one terminal of said condenser and the other end of said third reactance coil, a connection between the other terminal of the condenser and said other conductor of the current supply line, said first and third reactance coils and said condenser forming a circuit in partial resonance at the frequency of the current supply line.
